MATERIAL HANDLING APPARATUS

Ryan Backofen and George L. Turner, Battle Creek, Mich., assignors to Clark Equipment Company, Buchanan, Mich., a corporation of Michigan

Application February 25, 1946, Serial No. 649,904

7 Claims. (Cl. 214—66)

1

Our invention relates generally to material handling apparatus and it has particular relation to apparatus for bodily transporting one or more stacks of boxes of citrus fruit or the like.

As set forth in the copending application of Robert H. Braun, Serial No. 645,193, filed February 2, 1946, and now abandoned, it has been the practice prior thereto to manually handle and transport single stacks of boxes of citrus fruit and the like from and to a warehouse or storage building. Because of the limitations in the manually operable apparatus of the prior art, such operations have been relatively slow and consequently have been comparatively expensive. Moreover they have been somewhat dangerous because of the likelihood of the stack being manually transported tipping or falling and injuring personnel in the vicinity.

The problem thus presented is to provide for readily and expeditiously handling one or more, preferably two or more, stacks of boxes of citrus fruit or the like at the same time. As indicated in the copending application of Braun above referred to various solutions to this problem are there set forth. In general they contemplate attaching auxiliary clamping and lift apparatus to a conventional fork lift truck. The arrangement is such that two or more stacks of boxes can be simultaneously clamped at the ends of the bottom boxes and at the same time the top of the stacks can be clamped with a force acting longitudinally thereof for steadyng the stacks and preventing falling or tipping thereof.

The present invention constitutes an improvement over that disclosed in the Braun application. In particular it has to do with the manner in which the clamping pressure is applied to the bottom boxes of the stack or stacks for lifting the same and the application of longitudinal pressure thereto for steadyng the stack or stacks during handling.

Accordingly an object of our invention, generally stated, is to provide apparatus for handling one or more stacks of boxes of citrus fruit or the like which shall be simple and efficient in operation and which may be readily, economically and safely used.

Among the objects of our invention are: to clamp the bottom box or boxes of the stack or stacks with a force that is proportional to that required to lift the load; to use the lift mechanism of a conventional industrial truck to provide the clamping force that is applied to the bottom boxes; and to employ the weight of the load compressor at the top of the stack or stacks to steady the same.

2

Other objects of our invention will in part be obvious and in part appear hereafter.

Our invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of our invention reference may be had to the following detailed description taken in connection with the accompanying drawings in which:

Figure 1 is a view, in side elevation, of the front portion of a conventional industrial truck on which is mounted material handling apparatus constructed in accordance with our invention;

Figure 2 is a view, in front elevation, of the apparatus shown in Figure 1, the clamps being shown in their wide open positions;

Figure 3 is a view, in front elevation, of the lower portion of the apparatus shown in Figure 2, the clamps being shown in the closed or gripping positions; and

Figure 4 is a top plan view of the clamp mechanism shown in Figure 3.

Referring now particularly to Figures 1 and 2 of the drawings, it will be noted that the reference character 10 designates generally a conventional industrial truck of the fork lift type, the front wheels of which are indicated at 11.

The truck 10 is provided with the conventional lift mechanism indicated generally at 14. This lift mechanism 14 includes a pair of upright channel members 15 joined at their upper ends by a cross member 16. Hydraulic lift mechanism is shown generally at 17 and comprises a hydraulic cylinder 18 with which a head or yoke 19 cooperates to move relative thereto when hydraulic pressure is applied to the cylinder 18. At the opposite ends of the head or yoke 19 sprockets 20 are rotatably mounted over which lift chains 21 extend. The upper end of each of the lift chains 21 is attached to a cross bar 22 extending between the channel frame uprights 15. The lower ends of the chains 21 are attached to lift mechanism in a manner which will be described hereinafter.

With a view to handling one, two, or more stacks of boxes of citrus fruit or the like, a movable frame shown generally at 26 is carried by the frame 14. The frame 26 includes upright channel frame members 27 which are secured

at their lower ends as by welding to a frame plate 28. From what has been said it will be understood that a relatively rigid frame 28 is provided by the upright members 27 and the frame plate 28.

Now in order to clamp the ends of the bottom boxes of the stack or stacks, clamp members shown generally at 29 and 30 are provided at opposite ends of the frame plate 28. The clamp members 29 and 30 comprise eveners 31 and 32 having inwardly extending tines or pointed projections 33 and 34 to facilitate gripping the box ends and preventing relative slippage. The eveners 31 and 32 are pivotally mounted as indicated at 35 and 36 on brackets 37 and 38 which are integrally formed with and extend at right angles to slides 39 and 40. It will be observed that the slides 39 and 40 are slidably mounted in guides 41 and 42 which may be integrally formed with the frame plate 28. It will now be apparent that the clamp members 29 and 30 are mounted for movement toward and away from each other so as to grip or release the bottom boxes of stacks of boxes positioned therebetween.

In order to move the clamp members 29 and 30 into clamping engagement levers 47 and 48 are pivotally mounted as indicated at 49 and 50 on the rear side of the frame plate 28. The levers 47 and 48 may be bell cranks or generally triangular shaped, as illustrated in the drawings. They may be provided with bolts 51 and 52 which extend through the slides 39 and 40 so as to provide mechanical connection thereto. Slots 53 and 54 are provided in the frame plate 28 to permit relative longitudinal movement of the bolts 51 and 52. Likewise slots 55 and 56 are provided in the levers 47 and 48 to permit relative movement of the bolts 51 and 52 when the former are rocked to and from the clamping positions thereof.

Now it is desirable to apply sufficient clamping force to the ends of the boxes between the clamp members 29 and 30 so that the boxes thereabove in the stacks can be lifted by force applied through the bottom boxes. In accordance with our invention this clamping force is proportional to the weight of the stacks being lifted. This is accomplished by mechanically connecting the lower ends of the lift chains 24 to the levers 47 and 48 as indicated at 57 and 58. Thus it will be understood that the clamp arms 29 and 30 are moved toward each other into clamping engagement when the hydraulic lift mechanism 17 is operated to move the head or yoke 18 upwardly. After the clamp members 29 and 30 have moved into the clamping position, as shown more clearly in Figures 3 and 4 of the drawings, the continued upward movement of the head or yoke 18 lifts the frame 27 and bodily lifts the stack or stacks of boxes which are gripped by the clamp members 29 and 30.

In order to facilitate the upward movement of the frame 27 rollers 59 and 60 are suitably mounted on the rear of the frame plate 28 and are guided in the channel upright frame members 15, as shown in Figures 2 and 4 of the drawings.

In order to bias the clamp members 29 and 30 to the unclamped or wide open positions springs 61 and 62 may be provided. Thus, when the hydraulic lift mechanism 17 is lowered, the springs 61 and 62 serve to bias the clamp members 29 and 30 to the positions thereof, shown in Figure 2 of the drawings.

Since each stack being transported by the ap- 77

paratus of our invention contains several boxes, for example nine boxes as indicated by the broken outline thereof in Figure 1, it is desirable that means be provided at the upper end of the frame 28 for steadyng the stack or stacks during handling. For this purpose a load compressor, shown generally at 63, may be used. The load compressor 63 may comprise a shelf-like plate 64 from which arms 65 extend for slidably mounting in the channel uprights 27 of the frame 28. Transverse pins 66 may be provided in suitable openings 67 in the arms 65 for limiting the downward movement of the load compressor 63. On the underside of the plate-like shelf 64 there may be provided a pad 68 of resilient material such as sponge rubber which serves to engage the top boxes of the stacks without marring or bruising the same.

It will be understood that the pins 66 are positioned in apertures 67 in the arms 65 in accordance with the height of the stack or stacks which are to be transported. They are so positioned that the weight of the load compressor 63 will be borne solely by the stacks of boxes clamped between the clamp members 29 and 30. In this manner a steadyng action is provided for the stacks so that while they are being transported by the truck 10 any tendency to fall or tip is overcome.

In operation the operator drives the truck 10 toward the stack or stacks of boxes that are to be picked up and transported. Ordinarily these stacks of boxes are spaced apart a slight distance in order to permit free circulation of air or gas therebetween for preservative purposes. It is desired to maintain this spacing of the stacks while they are being transported so that it will be unnecessary to re-handle them to again provide this spacing. When the present invention is used, two or more stacks of boxes can be picked up readily and the spacing therebetween maintained, as will be readily understood.

The stacks of boxes are approached with the clamp members 29 and 30 in the wide open position, as shown in Figure 2 of the drawings. The load compressor 63 is elevated to such position that it will readily clear the upper boxes of the stacks.

When the truck 10 has been moved to such position that the stacks to be transported are properly located between the clamp members 29 and 30, the load compressor 63 is released as by removing the pins 66 so that the pad 68 thereof rests on the upper sides of the top boxes of the stacks. The weight of the load compressor 63 is thereby transmitted to the stacks in the application of force acting longitudinally thereof. The hydraulic lift mechanism 17 is then actuated. First the clamp members 29 and 30 are drawn inwardly against the biasing force of the springs 61 and 62 so as to clamp the bottom boxes of the stacks therebetween. When the clamp members 29 and 30 reach the limit of their inward travel, as controlled by the dimensions of the bottom boxes, the continued operation of the lift mechanism 17 causes the stacks to be lifted on upward movement of the frame 28. The stacks need be lifted only a slight distance to clear the floor and then may be transported by the truck 10 to the desired location.

The foregoing sequence of operations is reversed in lowering the stacks of boxes at the desired location. The truck 10 may then be returned by repeating the operation.

Since certain changes can be made in foregoing construction and different embodiments of the invention can be made without departing from the spirit and scope thereof, it is intended that all matters shown on the accompanying drawings or described herebefore shall be interpreted as illustrative and not in a limiting sense.

We claim as our invention:

1. For combination with an industrial truck having a pair of vertically movable lift chains, a frame adapted to be mounted for vertical movement on the truck for transporting a plurality of stacks of boxes or the like, a pair of arms swingably mounted near the lower end of said frame for engaging the opposite sides of the bottom boxes of the stacks, and a pair of bell cranks pivoted on said frame and each operatively connected at one end to one of said arms for moving the same and at the other end to one of said lift chains, the upward movement of said lift chains causing upward movement of said frame and at the same time causing said arms to grip said bottom boxes with a force proportional to the weight of the stacks being lifted.

2. For combination with an industrial truck having a pair of vertically movable lift chains, a frame adapted to be mounted for vertical movement on the truck for transporting a plurality of stacks of boxes or the like, a pair of arms swingably mounted near the lower end of said frame for engaging the opposite sides of the bottom boxes of the stacks, a pair of bell cranks pivoted on said frame and each connected at one end to one of said arms for moving the same and at the other end to one of said lift chains, the upward movement of said lift chains causing upward movement of said frame and at the same time causing said arms to grip said bottom boxes with a force proportional to the weight of the stacks being lifted, and a load compressor slidably mounted at the upper end of said frame for engaging the top boxes of said stacks to hold the same in place while they are being transported by the truck.

3. For combination with an industrial truck having a pair of vertically movable lift chains, a frame adapted to be mounted for vertical movement on the truck for transporting a plurality of stacks of boxes or the like, a pair of brackets swingably mounted near the lower end of said frame, an evener pivoted intermediate its ends on the outer end of each bracket for engaging the ends of the bottom boxes of the stacks, and a pair of bell cranks pivoted on said frame and each connected at one end to one of said brackets for moving the same and at the other end to one of said lift chains, the upward movement of said lift chains causing upward movement of said

frame and at the same time causing said brackets to swing toward each other thereby moving said eveners into engagement with the ends of said bottom boxes with a force proportional to the weight of the stacks being lifted.

4. For combination with an industrial truck having a vertical frame and cooperating vertically movable lift means, a lift frame arranged and adapted to be movably mounted on and guided by said vertical frame, a pair of arms extending forwardly of and movably mounted near the lower end of said lift frame for engaging the opposite sides of an object therebetween to be transported, and a pair of levers pivoted on said lift frame for movement at right angles to said arms and operatively interconnecting the same and said lift means whereby on upward movement of said lift means said lift frame is moved upwardly and said arms are moved toward said object to grip the same with a force proportional to the weight thereof for lifting the same.

5. The invention, as set forth in claim 4, wherein a spring means is provided for urging said arms apart to the unclamped position.

6. The invention, as set forth in claim 4, wherein in each arm includes a slide that is mounted on the lift frame for horizontal endwise movement, a bracket integrally formed therewith and extending forwardly thereof, and an evener pivoted intermediate its ends on the outer end of said bracket.

7. The invention, as set forth in claim 6, wherein a spring reacts between the lift frame and each arm for moving the arms apart to the unclamped position.
